UNITED STATES PATENT OFFICE.

FAUSTIN PRINZ, OF MILWAUKEE, WISCONSIN.

MIDDLING-PURIFIER.

SPECIFICATION forming part of Letters Patent No. 375,194, dated December 20, 1887.

Application filed February 2, 1885. Serial No. 154,620. (No model.)

To all whom it may concern:

Be it known that I, FAUSTIN PRINZ, a subject of the Emperor of Germany, residing at Milwaukee, in the county of Milwaukee and State of Wisconsin, have invented certain new and useful Improvements in Middlings-Purifiers; and I do hereby declare the following to be a full, clear, and exact description of the invention, such as will enable others skilled in the art to which it appertains to make and use the same.

Figure 1 is a longitudinal vertical section through a middlings-purifier. Fig. 2 is a vertical cross-section through the same on the line $x x$ of Fig. 1. Fig. 3 is a cross-section through a bolting-frame, showing my invention applied to a large size frame. Fig. 4 is a perspective view of a piece of a bolting-cloth with my invention applied thereto.

20 My invention has for its object to provide means to clear the meshes of bolting-cloth; and to such ends the invention consists in the construction and the combinations of parts, hereinafter particularly described, and then 25 specifically defined by the claims.

In the drawings, the letter A designates a middlings-purifier casing of ordinary construction provided with a fan, B, in its upper part for creating a current of air through the side 30 openings, C, and thence upward through the shaking frame D into the fan-box, from whence it escapes, as usual. The fan is rotated by belting connected to the pulley E, and the shaker-frame is suspended in the ordinary way 35 by straps F and is reciprocated by a rod, G, having an eccentric connection with a shaft at the end of the casing, the eccentric and shaft not being shown, and in the lower part of the casing is a screw-conveyer, H, of ordinary construction for carrying off the middlings.

40 I have illustrated but a single conveyer and a single shaker-frame, although there may be a series of both, as commonly practiced, as my invention is just as applicable where there are 45 many as where there is only one shaker-frame used. Heretofore, when knockers have been used to strike the cloth to jar the same, the stroke has been such as to force the cloth out from the parallel plane of its surface.

50 In order to give a movement in the direction of the plane of the cloth and obtain better re-

sults, I attach a plate or strip of wood or other suitable material to the cloth disconnected from any rigid part of the shaker-frame, which strip or plate is jarred or moved by a knocker operated by the reciprocation or movement of the frame, so as to jar the cloth in the direction of the plane of its surface, as distinguished from jarring it at an angle to the plane of the cloth, and thereby disengage the particles 60 clogging the mesh and dislodge the same by the draft of air passing through the meshes.

In the drawings I have illustrated a strip, I, secured to the bolting-cloth J by nails or other means, with its ends free from rigid connection 65 with any part of the shaker-frame. To this strip there is screwed or otherwise secured a bracket or arm, K, on which slides a horizontal block, L, of metal, wood, leather, rubber, or other suitable material. On the same arm on 70 opposite sides of said block are stops or checks M to limit the throw of the block. One of these stops may be rigidly fixed to the arm, while the other may be adjustable thereon by means of a set-screw, a, so as to lengthen or 75 shorten the throw of the block. In the reciprocation of the shaker-frame the said block will be thrown or slid back and forth on its arms, so as to strike the stops or checks M in alternation, and thereby push or move the strip I in 80 the direction of the plane of the cloth, and the strip will jar the cloth in the same direction, so as to open the meshes of the cloth, and thus, assisted by the air passing through the cloth, dislodge the particles which tend to clog the 85 meshes. This construction not only jars the cloth in a line parallel with the plane of the cloth, but also acts more directly on the cloth and covers and operates on a larger area and more effectively clears the meshes of the cloth. 90

A single strip and single knocker are shown; but it is obvious that a number of them may be used running parallel with each other or arranged end to end, and instead of placing the strip lengthwise of the shaker-frame, 95 which, however, is the preferable way, it may be placed in any other relation to the length of the shaker. It is also obvious that instead of placing the knocker, constructed as described, over the cloth it may be placed beneath it.

Where the bolting-cloth is of a large size and

divided by a central strengthening partition, *b*, as illustrated in Fig. 3, there will be one of the knockers secured to each section of the cloth on opposite sides of said partition.

5 The shaker-frame is provided with the usual cross rods or strips, *d*, and the cloth with the usual strengthening or attaching strips, *e*. To deaden the noise of the knockers, the blocks may be cushioned with leather or other sound-deadening material.

In operation the shaker-frame *D* is moved in the usual way, and in its reciprocation the cloth is jarred in the direction of its plane by the knockers acting as described, so as to open 15 its meshes, and air is drawn through the side openings, *C*, and up through the meshes of the cloth and out through the fan box in the upper part of the casing *A*.

The meshes of the cloth are thus more effectively cleared than heretofore and the middlings more thoroughly purified.

I have illustrated my invention as applied to a middlings-purifier; but I do not mean thereby to restrict it to any particular form, 25 as it may be applied to any bolting-cloth, whether of fabric or metal, and where the action is such as to cause the said knockers to strike and jar the cloth, as described.

Having described my invention and set forth its merits, what I claim is—

1. The combination, with a bolting-cloth, of an arched arm connected with the cloth to move therewith and extended horizontally, and a block sliding on said arm and adapted to jar the cloth in a plane parallel with its surface, substantially as described. 30

2. A middlings-purifier comprising the following elements: a casing provided with air-inlet openings below a shaker-frame, a shaker-frame above said openings and having the 40 bolting-cloth secured thereto, a fan to create a draft of air through the bolting-cloth, an arched arm connected to the cloth to move therewith and extended horizontally, and a block sliding on said arm and adapted to jar the cloth in a 45 plane parallel with its surface, substantially as described.

In testimony whereof I affix my signature in presence of two witnesses.

FAUSTIN PRINZ.
